HOT AIR FURNACE

Clifford Blair, Ironton, Ohio

Application August 14, 1940, Serial No. 352,607.

3 Claims. (Cl. 126—99)

This invention relates to a hot air furnace and has for an object to provide a furnace in which the gases pass from an enclosed radiant combustion chamber through oppositely disposed horizontal tubes arranged in zigzag fashion upwardly to opposite sides of the furnace and terminating in a common header from which the gases pass into the chimney, to more uniformly heat air draft passing through the furnace at every point thereof than hitherto possible in conventional hot air furnaces.

A further object is to provide a hot air furnace in which the air is drawn in from the top of the furnace through a grille which divides the air draft into fine streams, the air passing around the convolutions of the tubes to be uniformly heated at every part of the furnace, and then being drawn from the furnace by a fan to be supplied to the rooms to be heated, the air thus passing from the furnace through a grille, both grilles and the suction of the fan tending to rarefy the air draft and speed it up to promote more uniform heat thereof than where the air is forced through the furnace and thus compacted by a pressure fan which latter has been found in practice to retard proper heating of the air during passage through the furnace.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawings forming part of this specification:

Figure 1 is a transverse sectional view of a hot air furnace constructed in accordance with the invention and taken on the line 1—1 of Figure 2.

Figure 2 is a longitudinal sectional view of the hot air furnace taken on the line 2—2 of Figure 1.

Figure 3 is a horizontal sectional view of the hot air furnace taken on the line 3—3 of Figure 2.

Figure 4 is a plan view of the blank from which one of the sections of the radiant combustion chamber is formed.

Figure 5 is a plan view of one of the sections of the combustion chamber.

Figure 6 is a detail elevation of one of the fins which are secured to the horizontal tubes, 5 with the parts separated.

Figure 7 is a cross sectional view of one of the fins in position on a tube.

Referring now to the drawings in which like characters of reference designate similar parts 10 in the various views, 10 designates the casing of the furnace within which is disposed a combustion chamber 11 the wall of which is constructed of sections 12 hereinafter more fully described in detail. The combustion chamber extends the 15 length of the casing and is spaced from the sides of the casing, access to the combustion chamber being had through a removable plate 13, best shown in Figure 2. The firepot is supported upon legs 14, best shown in Figure 1, and the bottom portion of the casing is divided 20 longitudinally by division walls 15 disposed adjacent the legs to provide air ducts 16, 17 and 18, the center air duct communicating with the combustion chamber through openings 19 formed in a grille 20 which extends transversely of the bottom portion of the casing and also co-acts 25 in supporting the combustion chamber. The center air duct 17 supplies air for combustion to a conventional radiant heater 21, the fuel pipe 30 22 of which enters the casing wall, as shown best in Figure 2.

A grille 23 having openings 24 therein closes the top of the furnace casing and forms the bottom of a cold air return flue 25 through which 35 cold air is drawn downwardly through the casing and through the openings 19 in the bottom grille 20 and into the hot air ducts 16 and 18 for supplying the rooms to be heated.

Disposed within the casing 10 above the combustion chamber are a plurality of heating tubes 26 arranged to conduct the hot gases of combustion upwardly in a circuitous zigzag path from the combustion chamber to a header 27 extending longitudinally of the casing near the top thereof 45 and adapted to be connected to the chimney. Each tube comprises superposed horizontal portions 28 extending from side to side of the casing and connected at their ends by elbows 29, as best shown in Figure 1. This arrangement of the tubes assures of the down air draft becoming thoroughly heated and uniformly heated 50 throughout every part of the furnace.

A plurality of water containers 30 are disposed in the casing 10 and are connected by a supply pipe 31, best shown in Figure 1. The water

supply in the containers for humidifying the heated air is automatically controlled by a valve 32 operated by a float 33 in a supply tank 34 disposed outside of the casing 10, the valve controlling a water supply pipe 35 in the usual manner.

A drain pipe 36 extends downwardly from the header 27 to catch condensation. The header is provided with a cover 37 at one end to permit access to the header when necessary.

The weight of the tubes 26 is supported by a frame comprising a plurality of superposed horizontal bars 38 which are bolted at the ends as shown at 39 to vertical bars 40, the latter being bolted to the casing as shown at 41. Other means connecting the bars of the frame together may be used.

As best shown in Figure 3, the air ducts 16 and 18 of the furnace are extended outwardly beyond the furnace as shown at 42 and 43, the extended portions of the air ducts converging at the intake end 44 of the conventional blower 45 having a driving pulley 46 which may be driven from any suitable source of power. The outlet duct 47 of the blower conducts the heated humidified air from the furnace to the room to be heated.

The wall of the combustion chamber is composed of sections each formed from a single blank 48 of sheet metal of substantially rectangular cross section provided with aligned transversely disposed slits 49 at the upper end extending about one-third of the way across the blank. The blank is also provided with longitudinal score lines 50 and 51 near the end of one of the slits and with score lines 52 and 53 near the end of the other slit. Between the score lines 50 and 51 a row of openings 54 is formed and between the score lines 52 and 53 a row of openings 55 is formed.

The blank shown in Figure 4 is bent at the slits 49 to form an inclined top wall section 56 of the combustion chamber as shown in Figure 1 and to form a vertical side wall section 57 as also shown in this figure. The blank is bent along the score lines to provide diverging fins 58, as best shown in Figure 3. The blank is also bent along the score lines to provide straight flanges 59. In assembling the combustion chamber the flanges 59 of each two adjacent vertical sections 12 have the rows of openings 54 and 55 in alignment and through these aligned openings securing bolts 60 are passed to assemble the sections. The inclined top wall portions 56 of the sections are connected by a top plate 61, best shown in Figure 1, through which top plate the lower ends of the tubes 26 communicate with the combustion chamber.

A flame spreader 62 is secured in the combustion chamber between the bar of radiants 21 to spread the flame against the inclined sections 56 of the firepot.

The horizontal portions 28 of the tubes 26 are provided with fins, one of which is shown in Figure 6. Each fin comprises two semi-circular sections 63, one having a flange 64 extending from one face of the section and the other having a flange 65 extending from the opposite face of the other section. The flanges are adapted to extend beyond the horizontal portions 28 of the tubes, as best shown in Figure 2. To assemble the sections bolts 66 are passed through open-

ings 67 in the ends of the sections. These fins radiate heat from the horizontal portions of the tubes to uniformly heat the air draft passing downwardly in the furnace over the tubes.

5 The elbows 29 of each tube 26 likewise are provided with fins designated in general by the numeral 68 and these fins are a duplicate of the fins just described, only larger to encircle the elbows, so that a detailed description will not be given.

Since the operation of the parts has been described as a description of the parts progressed, it is thought the invention will be fully understood without further explanation.

What is claimed is:

1. A hot air furnace, comprising a casing, a restricted air supply channel across the upper end of the casing, a combustion chamber in the lower end of the casing and having its upper end formed of converging wall members connected by a horizontal top wall, a plurality of tubes connected to the conical upper end of the combustion chamber with superimposed horizontal convolutions, a header extending across the casing below and spaced from the air supply channel, and having the tubes connected to the sides thereof, and air ducts communicating with the casing at each side thereof below the lower end of the combustion chamber.

2. A hot air furnace, comprising a casing, a restricted air supply channel across the upper end of the casing and having openings communicating therewith, a combustion chamber centrally located in the casing above the lower end thereof and provided with its upper end formed of converging wall members connected by a horizontal top wall, a plurality of tubes connected to the horizontal top wall end of the combustion chamber with superimposed horizontal convolutions, a header extending across the casing below and spaced from the air supply channel with the upper ends of the tubes connected to the sides thereof, a passage below the combustion chamber, and an air passage communicating with the casing on each side of the first mentioned passage and converging into a single discharge opening.

3. A hot air furnace, comprising a casing, a restricted air supply channel across the upper end of the casing and communicating therewith, a combustion chamber within the casing above the lower end thereof with its upper end formed of converging wall members connected by a horizontal top wall, a plurality of tubes connected to the horizontal top wall of the combustion chamber with superimposed horizontal convolutions, a header extending across the upper end of the casing below the air supply channel and spaced therefrom and having one end connected to a flue, the horizontal convolutions of the tubes connected to the sides of the header, a heater in the combustion chamber, a passage below the combustion chamber for supplying air to the heater, and an air discharge passage communicating with the casing on each side of the air supply passage for the heater and converging into a single discharge opening.

CLIFFORD BLAIR.
